UNITED STATES PATENT OFFICE.

EWALD PRAEGER, OF SAN ANTONIO, TEXAS.

HOLDER FOR ICE-CREAM FREEZERS.

996,137.

Specification of Letters Patent. Patented June 27, 1911.

Application filed March 8, 1911. Serial No. 613,109.

To all whom it may concern:

Be it known that I, EWALD PRAEGER, a citizen of the United States, residing at San Antonio, in the county of Bexar and 5 State of Texas, have invented a new and useful Holder for Ice-Cream Freezers, of which the following is a specification.

This invention relates to refrigeration, and more especially to ice cream freezers; and 10 the object of the same is to produce an improved attachment thereto for holding the body of the freezer upon a suitable support such as a table top. This object I accomplish by the construction of holder herein- 15 after more fully described and claimed, and as shown in the drawings wherein—

Figure 1 is a perspective view of a table and of the body of an ice cream freezer standing thereon and partly broken away to 20 show my improved holder in place. Fig. 2 is a sectional view through the same. Figs. 3 and 4 are enlarged perspective details of the members of the holder itself.

In the drawings the letter T designates a 25 table such as is ordinarily employed in the kitchen, and the letter I designates the body of an ice cream freezer in the present instance, the same being made up of staves projecting at their lower ends below the bottom B to form the chime, and held in place 30 by hoops H as usual. It is well known to the house wife that in making ice cream when the same begins to stiffen it sets up considerable resistance to the rotation of the 35 handle, and she finds it irksome to hold the body of the freezer with one hand and rotate the handle with the other, but unless she does so she is apt to over-turn the freezer and in any event the continued rotation of 40 the handle will jiggle the freezer around upon the table top and scratch it and possibly cause the freezer to fall off. I might here state that to an extent the same difficulty is often experienced with other ma- 45 chines such as small churns or mixing or agitating machines of many varieties, but my present attachment is intended more particularly to bodies whose bottoms are raised as by the presence of a surrounding chime.

Coming now more particularly to the 50 details of the present invention, the same is made in two metallic members which are preferably galvanized or otherwise treated to prevent rusting and which are so shaped 55 and located as to be almost if not completely hidden whether in use or not, and in the case

of an ice cream freezer these members can be packed within the freezer and will add but little to its expense and practically nothing to its cost of transportation. The member shown in Fig. 3 is a keeper made of strap metal (or it might be of cast iron) and comprises two extremities or ears 5 pierced with eyes or holes 6 for the passage of screws 7 or bolts 8 (both are indicated in 60 this view); and a body between the inner ends of said ears consisting of dropped arms 9 and a flat plate 10 connecting their lower edges. In order that this member may be as small as possible, one edge of the plate 65 10 may be bowed outward as at 11 to accommodate a square hole 12 which extends through the plate 10 at about its center, and from this hole to the other edge 13 of the plate extends a narrow slot 14. The other 70 member is shown in Fig. 4 and consists of a bolt and its thumb nut. The head 21 of this bolt is by preference made quite flat as shown, just beneath the head the bolt is squared as 75 shown at 22, and the shank 23 beneath the 80 said squared portion is round and is threaded at its lower end as shown at 24; and on this threaded portion is screwed a thumb nut 25 having rather large wings as shown. The diameter of the round shank 23 is about 85 the same as the width of the slot 14, and the squared portion 22 is of a size to fit closely within the square hole 12. Bolts of this character are now on the market and can 90 be purchased in large quantities and at 95 slight expense, and the member shown in Fig. 3 can be made to correspond.

The manner of attachment and the use of this device will now be explained.

It is necessary to provide the table top T 95 or other support with a round hole 30 (although it might be of other shape) of a size to permit the squared portion 22 of the bolt to drop therein, so that when this device is not in use the flattened head 21 of the bolt 100 will project above the table top only for a very slight distance as will be clear. The other member is attached to the bottom B of the freezer by means of bolts 8 as shown in Figs. 1 and 3 or preferably by means of 105 screws 7 whose tips would not pass upward through the bottom and hence would not cause any leakage of the latter; but it is essential that the arms 9 of this member shall not be of such length that the base plate 10 110 thereof will project below a line drawn across the lower extremity of the body I.

In other words, the entire member must be of less vertical height than the depth of the chime C, by which of course it will be hidden at all times. To use the attachment, the 5 freezer is brought into position upon the table, the thumb nut 25 loosened and run down upon the threads 24, the entire bolt lifted with one hand and held elevated until its head 21 rests against the lower face of 10 the bottom B, and then the freezer moved with the other hand so that the slot 24 engages the shank 23 of the bolt and the latter has been caused to travel along the same until its squared portion 22 can be dropped 15 into the square hole 12. Thereafter the thumb nut 25 is tightened up, and the obvious result is that the freezer is held firmly upon the table top so that the tendency to rock the freezer in place or to tip it over is 20 avoided. After the machine has been used, it can be disconnected by a reversal of the operation just described.

What is claimed is:

The herein described holder for ice cream 25 freezers and like machines having a raised

bottom surrounded by a chime, the same comprising a metallic member consisting of two perforated ears, arms depending from their inner ends for a distance less than the height of said chime, and a plate connecting the 30 lower ends of said arms and having a slot projecting from one edge toward the center of the plate and a square hole communicating with the inner end of said slot; and a second member consisting of a bolt adapted 35 for insertion through a table top or other support, and having a flattened head, a squared portion just beneath the head and of a size to fit in said square hole, a reduced shank depending from said squared portion 40 and threaded, and a thumb nut adapted to take onto said threaded end, the whole for use substantially as hereinbefore described.

In testimony that I claim the foregoing as my own, I have hereto affixed my signature 45 in the presence of two witnesses.

EWALD PRAEGER.
